UNITED STATES PATENT OFFICE.

CHARLES S. WOODS, OF INDIANAPOLIS, INDIANA.

ICE CHIPPER.

1,409,989.

Specification of Letters Patent. Patented Mar. 21, 1922.

Application filed June 13, 1921. Serial No. 477,114.

To all whom it may concern:

Be it known that I, CHARLES S. Woods, a citizen of the United States, and a resident of Indianapolis, county of Marion, and State of Indiana, have invented a certain new and useful Ice Chipper; and I do hereby declare that the following is a full, clear, and exact description thereof, reference being had to the accompanying drawings, in which like numerals refer to like parts.

This invention relates to an ice chipping machine wherein a heat insulated cabinet is adapted to receive a cake of ice and retain the same until such time as chipped ice is to be secured therefrom, and preferably such a cabinet is a refrigerator.

The chief object of this invention is to provide a cabinet which is adapted to retain a cake of ice and provide said cabinet with ice chipping means and their associated mechanism whereby ice may be chipped from the cake or mass, as desired, for use with a minimum of wastage and a maximum efficiency.

The main feature of the invention consists in providing the machine with means for agitating the ice when it has become worn away by the chipping process. Wherein the ice is held in fixed position by the sides of the container or hopper either because of the particular size of the cake or by the wedging of a plurality of cakes, it will soon be worn away where it is chipped so that the chipping teeth on the revolving drum will cease to engage the ice. It is then necessary to agitate the ice so as to cause it to take a new position in the container or hopper wherein it will fall by gravity into engaging position with the chipping teeth.

To this end agitating prongs are provided which take an inoperative position when the drum is being rotated in one direction for agitating the ice and will take an operative position when rotated in the opposite direction for agitating the ice and cause it to take a new position.

The full nature of this invention will be understood from the accompanying drawings and the following description and claims.

In the drawings Fig. 1 is a front elevational view of a refrigerator embodying the invention. Fig. 2 is an enlarged sectional view taken on the line 2-2 of Fig. 1 and in the direction of the arrows. Fig. 3 is a sec-

tional view of the ice chipping means shown in Fig. 2.

In Figs. 1 to 3 inclusive there is illustrated the preferred form of the invention and the same shows a refrigerator 210 of the usual type having the usual doors 209 to provide entrance for articles of food and the like which are to be kept cool. 208 indicates a door on the refrigerator through which ice is admitted to the ice storage chamber. The usual door positioned beneath the door 208 is illustrated as being replaced by a panel 207 which contains a drawer 206 in the base portion thereof.

The customary partition wall between the ice chamber and the lower cooling chamber is replaced by an inclined hopper and base 213 in the chute of which is positioned an ice chipping drum 216 which carries the teeth 217 on the periphery thereof. The wall of the chute or hopper 213 is provided with downwardly directed retaining teeth 221 and also associated with the drum 216 is the agitating means 226.

In the event that the ice 11 becomes clogged the drum 216 may be reversed by the handle 220 and on said drum there is positioned a plurality of agitating prongs 230 which normally are seatable in slots 231, but which upon reverse rotation of the drum are projected outwardly therefrom to move the ice and thereby break up the jam. The refrigerator, as is customary, is provided with a drain 231 into which the drainings from the melted ice are discharged. The drawer 206 is provided with suitable perforations 205 so that the chipped ice retained therein will be retained in a relatively dry condition.

The invention claimed is:

1. In an ice chipping machine having a housing with an ice hopper therein, a chipping drum adapted to be revolved in one direction within said housing for engaging and chipping the ice therein, and means for agitating the ice and causing it to move into a new position so as to reengage said chipping drum when cut away and out of chipping engagement therewith.

2. In an ice chipping machine having a housing with an ice hopper therein, a chipping drum adapted to be revolved in one direction within said housing for engaging and chipping the ice therein, and prongs pivotally mounted upon said drum and pro-

jecting beyond the chipping teeth thereof for engaging and chipping the ice so as to cause it to take a new position and reengage said chipping drum when cut away and out 5 of chipping engagement therewith.

3. In an ice chipping machine having a housing with an ice hopper therein, a chipping drum adapted to be revolved in one direction within said housing for engaging 10 and chipping the ice therein, and a plurality of prongs pivotally mounted upon said drum so as to be inoperative while said

drum is turned in one direction and project radially from said drum in operative position when said drum is turned in the opposite direction, said prongs being arranged when in operative position to engage and agitate the ice for moving it into position to reengage said chipping drum upon the surface being cut away and out of chipping 15 engagement therewith.

In witness whereof, I have hereunto affixed my signature.

CHARLES S. WOODS.
